UNITED STATES PATENT OFFICE.

CARL H. BISSELL, OF SYRACUSE, NEW YORK, ASSIGNOR TO CROUSE-HINDS COMPANY, OF SYRACUSE, NEW YORK, A CORPORATION OF NEW YORK.

LAMP-SHADE HOLDER.

1,115,050.

Specification of Letters Patent.

Patented Oct. 27, 1914.

Application filed May 29, 1913. Serial No. 770,569.

To all whom it may concern:

Be it known that I, CARL H. BISSELL, of Syracuse, in the county of Onondaga and State of New York, have invented a certain 5 new and useful Lamp-Shade Holder, of which the following is a specification.

This invention has for its object the production of an incandescent electric lamp fixture and particularly of a fixture having a 10 simple, efficient and inconspicuous lamp shade holder, and the invention consists in the combinations and constructions herein-after set forth and claimed.

In describing this invention, reference is 15 had to the accompanying drawings in which like characters designate corresponding parts in all the views.

Figure 1 is an elevation, partly broken away, of this fixture, the spring jaws of 20 the shade holder being shown in their closed position. Fig. 2 is a vertical sectional view of the fixture showing the position of the jaws when in their open position, the lamp socket being shown in elevation. Fig. 3 is 25 an end view, looking upwardly in Figs. 1 and 2, the lamp socket and shade being removed. Fig. 4 is a detail view, partly in section, of the clamping nut.

The lamp shade holder is here shown as 30 embodied in a fixture including a cup shaped casing which supports the lamp socket and the shade holder, and the shade holder usually consists of spring arms having conically curved surfaces, these spring arms being 35 clamped into position on the shade by a clamping member as a nut encircling the arms.

1 is the casing which is here shown as cup or bell shaped, the casing having an internally threaded nipple 2 at its upper end for connection with a conduit as 3 inclosing the service wires and being open at its lower end. The casing is also formed with a bottom in the form of an annular flange 4 at 45 the base of the nipple 2.

5 designates the series of spring arms or jaws located within the casing 1, this series of jaws having an externally threaded conoidal surface 6, the base portion or portion of larger diameter being located nearer the free or engaging ends 7 of the jaws than the upper portion of less diameter. These spring jaws 5 are preferably formed in a cup shaped shell 8 having its bottom 55 9 inturned and engaging the bottom 4 of

the casing 1, the shell 8 being split longitudinally from its open end toward its bottom to form the spring arms 5. The lower or free ends 7 of the jaws engage the shade 10.

11 is the clamping element as a nut having an internally threaded conoidal surface 12 complementary to the surface 6 of the series of clamping jaws 5. The nut is preferably formed up out of sheet metal and is provided with an annular chamber 13 opening through its upper end for receiving the lower edge 14 of the casing 1.

15 is the lamp socket for receiving the incandescent electric lamp 16, the socket 15 having its base 17 mounted on the bottom 9 of the shell 8 so that the jaws 5 inclose the socket 15. The spring jaws 5 are secured to the bottom 4 of the casing by any suitable means as rivets 18 passing through the bottom 9 of the shell 8 and the bottom 4 of the casing 1, and the lamp socket is secured in position in any suitable manner as by screws which thread into openings 19 in the bottoms 4 and 9.

In operation as the nut 11 is screwed upwardly the jaws 5 will expand permitting the insertion of the lamp shade 10 and upon the downward movement of the nut, the jaws 5 are contracted on the lamp shade. This fixture and lamp shade holder presents a neat appearance and is particularly adapted to places where there is vibration as in railway cars.

What I claim is:

1. A lamp shade holder comprising resilient spring jaws for engaging the lamp shade, the jaws having conically curved threaded surfaces, and a clamping nut having complementary conical threaded surfaces for coacting with the threaded surfaces of the jaws, substantially as and for the purpose described.

2. A lamp shade holder comprising a circular series of spring jaws for engaging the lamp shade, the series of jaws having a conoidal threaded surface, and a clamping nut having a complementary internally threaded conoidal surface for engaging the threaded surface of said series of jaws, substantially as and for the purpose specified.

3. A lamp shade holder comprising a circular series of spring jaws for engaging the lamp shade, the series of jaws having an externally threaded conoidal surface having

its portion of greatest diameter located nearer the free ends of the jaws than its portion of less diameter, and a clamping nut threading on the series of jaws, substantially as and for the purpose set forth.

4. A lamp shade holder comprising a circular series of spring jaws for engaging the lamp shade, the series of jaws having an externally threaded conoidal surface having its portion of greatest diameter located nearer the free end of the jaws than its portion of less diameter, and a clamping nut threading on the series of jaws, and having an internally threaded conoidal surface complementary to the threaded surface of the series of jaws, substantially as and for the purpose described.

5. The combination of an electric lamp socket, and a shade holder comprising a series of spring jaws encircling the lamp socket and having a conoidal threaded surface, and a clamping nut turning on the threaded surface of said jaws, substantially as and for the purpose set forth.

6. The combination of a supporting casing open at one end, a lamp shade holder comprising a series of spring jaws extending into the casing, the series of jaws being provided with external threads, and a clamping nut having internal threads complementary to

those of the spring jaws, the clamping nut being formed with an annular chamber receiving the margin of the wall of the casing at the open end thereof, substantially as and for the purpose set forth.

7. The combination of a cup shaped casing open at one end, a lamp shade holder in the form of a shell having its bottom mounted on the bottom of the cup shaped casing, the shell being split longitudinally at a plurality of points forming spring jaws for engaging the shade, a clamping element encircling the series of jaws and having an annular chamber for receiving the edge of the cup shaped casing at the open end thereof, and an incandescent lamp socket within the holder and arranged with its base mounted on the bottom of the shade holder, substantially as and for the purpose described.

In testimony whereof I have hereunto signed my name in the presence of two attesting witnesses, at Syracuse, in the county of Onondaga, in the State of New York, this 13th day of May, 1913.

CARL H. BISSELL.
